UNITED STATES PATENT OFFICE.

JOHANN-GEORG STEIN, OF BERLIN-HALENSEE, GERMANY.

DIVING CONTRIVANCE ADAPTED FOR DEEP-SEA DIVING.

Application filed July 7, 1926, Serial No. 121,012, and in Germany March 20, 1925.

Diving bells which are attached to a cable or to a chain, and lowered from a steamer upon the bottom of the sea are well known. The range of action of diving bells of this type is however very limited as they are capable of working only directly underneath the vessel from which they have been lowered so that the vessel must remain accurately above the point at which the diving bell is working, 10 this being of course very difficult. Another inconvenience is that the diving bells while being lowered are tossed about just as much as the vessel itself unless the latter is anchored from all sides, this being however not 15 possible in many cases.

It has been proposed to move a sled-like contrivance, capable of holding a diver, over the sea-bottom from the vessel moving on the surface of the water. Such an apparatus 20 however could only operate in a very limited depth and at an enormous risk to the diver, since the vessel above could not stop quick enough should the sled strike against obstacles on the sea-bottom, such as a wreck, an 25 anchor, rocks or the like which, on account of the limited range of sight under water, would only be observed at the last moment. Neither of the above mentioned contrivances 30 enables the execution of diving expedition as neither are adapted for carrying complicated tools and the like, nor are they capable of carrying more than one man.

It has further been proposed to use an independent diving boat as accommodation for 35 the divers. Such contrivance would present the inconvenience that it has to be of comparatively large size because it must contain a large engine-plant with a large accumulator 40 plant for independent drive so that it could not be accommodated on a comparatively small-size vessel. The diving boat would have to be propelled to the point of use by its own power so that, eventually, besides the 45 electric driving means, an internal combustion engine would become necessary whereby the size of the diving boat would be further increased.

These disadvantages are obviated by the 50 invention as a submarine which, although constantly attached to the vessel on the surface of the water, has her own radius of independent action and is capable of independent movement, and can be accommodated in a shaft of the main vessel and carried to any 55 point at which it has to be used.

An embodiment of the invention is illus-

trated in the accompanying drawings in which:—

Fig. 1 shows in side elevation the main vessel carrying the submarine to the place of 60 destination.

Fig. 2 is a cross section through the point of the main ship where the submarine is located, on enlarged scale.

Fig. 3 is a longitudinal section of Fig. 2. 65

Fig. 4 illustrates on reduced scale the operation of the diving contrivance.

Fig. 5 shows how the submarine is hauled into the main vessel, also on reduced scale.

Fig. 6 shows in a partial longitudinal section 70 certain portions of the submarine.

Figure 7 is a detail of a cable supporting buoy.

According to this invention a submarine 1 is used which is permanently attached to a 75 main ship 3 by a strong cable 2 and carries as an engine only an electromotor for driving one or several propellers 4. The submarine has all the apparatus commonly used for a submarine, as horizontal rudders 5, 6, vertical 80 rudders 7, diving tanks, air tanks, trim tanks, air compressors and the like. Special arrangements are made to prevent the cable 2, which attaches the submarine to the main ship, from getting entangled with the propellers or interfering with the several rudders. With this object in view propeller- 85 protectors or rudder-protectors of known type are provided.

A small size storage battery serves for 90 emergency lighting and for driving the propeller for a short time in case the current supplied through the cable 2 should be interrupted.

In the main ship 3 a shaft 8 is provided 95 which has preferably inclined side walls 9 lined with wooden ribs 10. The front wall 11 and the rear wall 12 of the shaft are downwardly and outwardly inclined, the rear wall at an exceptionally large angle as shown at 100 12^a in Fig. 1, for reasons which will be explained hereinafter.

The main vessel is further equipped with a powerful steam winch, on the drum 13 of which the cable 2 is wound up. The cable 105 might further be wound only a few times around the winch drum the rest of the cable being stored in a special cable tank. This cable is used for supplying to the submarine electric current for driving the propellers, the 110 pump and other tools, the cable comprising also telephone wires which provide constant

communication possibilities with the main ship.

The cable is conducted over a guide pulley 14 arranged in or above the shaft 8. The crown 5 is preferably attached to the submarine by means of lugs 16. For certain special cases it may be advisable to make the connecting point 17 between cable and crown adjustable, i. e. so that it can be shifted on the 10 crown. The walls of the shaft are protected by strong frames 20 braced against the frames and other building elements of the vessel, and strong reinforcements are provided at the mouth of the shaft and higher up in order to 15 compensate for the weakening of the hull of the vessel caused by the shaft, for example a frame 21 and a strong stringer 22.

The submarine itself is preferably composed of several cast steel rings 23, in order 20 to be capable to withstand the pressures to which it will be exposed, said rings 23 being joined either by means of bevelled faces or by the interposition of a metal packing 24 by 25 means of screws or in any other convenient manner.

The submarine is subdivided into several compartments in the usual manner by means 30 of transverse bulk heads, lenses 25 and 26 being arranged in the forward frame, the lens 25 being designed to allow the light rays produced by a high-powered search light to pass, and the other lenses 26 serving as observation holes. At the bow or at the sides tools may be arranged which are adapted to 35 be operated from inside the submarine. A man-hole having a trap door 27 commonly used in diving boats serves as entrance. The measurements of the shaft 8 are chosen so that the upper portion of the submarine is above 40 the water-line when it is being transported by the main ship.

The contrivance operates as follows:—

The submarine is transported by the main vessel in the shaft 8 to the place of destination. At this place the submarine is lowered 45 by means of the cable 2 so that it is capable of executing independent movements in the direction of the keel in any corresponding direction, in order to locate for example first 50 a wreck 28 resting on the bottom of the sea and then to carry out the necessary operations.

For carrying the weight of the cable buoys 29 may be attached to the cable when the cable 55 is being unwound, so that by their buoyancy they intercept a part of the weight of the cable. These buoys will be hereinafter described.

The submarine is provided with a circular 60 compass which is connected by the cable to a compass on the main vessel so that the location of the submarine can always be accurately determined on the main ship.

The diving of the submarine is facilitated 65 by flooding certain compartments. The rais-

ing of the submarine is facilitated by emptying the flooding tanks.

At the hauling of the submarine it is advisable to bring the same, with regard to the main-ship, into the position shown in Fig. 5, 70 so that by means of the circular compass it can be brought into the central plane of the main ship, whereby the hauling into the shaft 8 is facilitated, specially if the rear wall of the shaft is strongly inclined towards 12°. 75

If the flooding tanks are completely emptied the submarine fits itself onto the inclined walls of the shaft 8 and can be lashed in this position so that no damaging of the submarine can be caused by the rolling and pitching 80 movements of the main vessel.

A submarine of this type can be used, not only for operations on wrecks, for deep-sea expeditions, but also for filming at great depths and the like. With this diving contrivance depths can be reached which have never been reached by diving apparatus and all sorts of expeditions can be carried out, to a certain extent independent from the anchorage or position of the main ship. 90

In a special form of construction of the invention the cable 2, which connects the submarine with the main ship, is not constructed from end to end as holding and lifting cable but only a short portion of the cable 2, which portion is attached to the submarine, the remainder of the cable being comparatively thin and just strong enough to carry its own weight and that of the thick portion and to withstand the oscillations which might occur in the cable. The thin portion of the cable serves merely for accommodating the conductors for the electric current and the telephone while the thick portion of the cable serves for lowering the 105 submarine from the shaft 8 and to haul the same into said shaft.

The buoys 29 designed to carry the cable are preferably of oviform shape so that they reduce resistance. In order to withstand the 110 water pressure at great depths they are inflated with air of high pressure. According to the depth for which the several buoys are designed, the inner pressure is higher or lower. The inside pressure of a buoy for about 2000 meters depth would amount to about 200 atm., and for 1500 meters depth to about 150 atm. Steel is used as material for the buoys. For inflating the buoys with air a valve 30 is provided. The cable 2 has 115 shackles 32, with rings to which the buoys are to be attached. Shackles 33 in the rings 31 carry each a roller 34 for guiding a cable 36 fixed to lugs 35 of the buoys. If the submarine and the main ship travel in the direction indicated by the arrow F the buoys adopt 125 approximately the position shown in Fig. 7.

I claim:—

1. A contrivance for deep-sea diving at very great depths comprising in combination 130

a main-vessel having in the interior a shaft open at the lower side and arranged to receive a submarine, a submarine adapted to be accommodated in the said shaft and an electric cable connecting the submarine to the main-vessel.

2. A contrivance for deep-sea diving at very great depths comprising in combination a main-vessel having in the interior a shaft of wedge-shaped cross section open at the lower side and having its longitudinal axis in the direction of the keel of the vessel and arranged to receive a submarine, a submarine adapted to be accommodated in the said shaft and an electric cable connecting the submarine to the main-vessel.

3. A contrivance for deep-sea diving at very great depths, comprising in combination a main-vessel, having in the interior a shaft of wedge-shaped cross-section open at the lower side and having its longitudinal axis in the direction of the keel of the vessel, the front and rear walls being inclined to the keel of the main-vessel and arranged to receive a submarine, a submarine adapted to be accommodated in the said shaft and an electric cable connecting the submarine to the main-vessel.

4. A contrivance for deep-sea diving at very great depths, comprising in combination a main-vessel, having in the interior a shaft of wedge-shaped cross section open at the lower side and having its longitudinal axis in the direction of the keel of the vessel, the front and rear walls being inclined to the keel of the main-vessel, the rear wall being more inclined than the front wall and ar-

ranged to receive a submarine, a submarine adapted to be accommodated in the said shaft and an electric cable connecting the said submarine to the main vessel.

5. A contrivance for deep-sea diving at very great depths, comprising in combination a main-vessel having in the interior a shaft of wedge-shaped cross section open at the lower side and having its longitudinal axis in the direction of the keel of the vessel, arranged to receive a submarine, a submarine bearing with the side walls against the side walls of the shaft and an electric cable connecting the submarine to the main-vessel.

6. A contrivance for deep-sea diving at very great depths, comprising in combination a main vessel having in the interior a shaft open at the lower side, arranged to receive a submarine, a submarine adapted to be accommodated in the said shaft and an electric cable connecting the submarine to the main-vessel and supplying the driving means of the submarine.

7. A contrivance for deep-sea diving at very great depths, comprising in combination a main-vessel, having in the interior a shaft open at the lower side, arranged to receive a submarine, a submarine adapted to be accommodated in the said shaft and an electric cable connecting the submarine to the main-vessel, supplying the driving means of the submarine and kept floating by a multiple or plurality of buoys arranged at distances apart.

In testimony whereof I affix my signature.

JOHANN-GEORG STEIN.
